Application November 23, 1940, Serial No. 366,872

9 Claims. (Cl. 178—7.5)

This application is a continuation in part of my application Serial No. 302,309, filed November 1, 1939.

My invention relates broadly to devices for reproducing optical images, and more particularly to a system and apparatus for reproducing such images which are sufficiently intense in light value as to be projected and magnified to form comparatively large fixed images.

Presently known television receivers and reproducers form the reproduced optical image by means of the action of a moving modulated electron beam which impinges on a fluorescing material, thus producing light due to the fluorescent properties of the material. It has been recognized, however, that there are definite limitations attendant the use of such material. The light formed is not sufficiently intense to be projected through a lens system onto a larger area with the formation of an adequately bright image due to the comparative feebleness of the light in the original image, both because of the fact that large amounts of light are lost in its transmission through lens systems and the fact that the amount of light (light flux in lumens) per unit area on the screen upon which the magnified image is cast varies inversely as the square of the ratio of respective linear dimensions between the magnified image and the image reproduced on the end of the tube.

The problem of providing a screen which will reproduce an optical image with a light sufficiently brilliant to be satisfactorily projected to large dimensions has been the subject of experimentation by a number of investigators. Screens have been provided of the so-called "thermal" type, that is, where the light produced is the direct result of the heating of the screen rather than that due to any inherent fluorescing properties, and so-called "thermal" screens or "thermal" images have been utilized for this purpose with varying degrees of success. Accordingly, it is one of the objects of my invention to provide suitable structures for the thermal formation of optical images due to the energy of impact of a scanning electron beam.

I have found that the shape of the scanning spot which is used plays an important part in the accurate reproduction of a thermal image. This spot should under some definite conditions vary from the circular, as is common practice today, to the elliptical in shape. Accordingly, it is another of the objects of my invention to provide means for varying the shape of the scanning spot with reference to the direction of motion

of the scanning spot and, in accordance with the modulation requirements, for the best delineation in the thermal image.

I have found that not only should the shape of the scanning spot be varied under definite circumstances, but that the size of the scanning spot also may be varied in accordance with the variation in the modulation of the beam, and it is a further object of my invention to vary the size of the electron scanning spot in accordance with variation in intensity of the electron beam for the purpose of securing optimum delineation in the thermal image.

One of the drawbacks inherent to the previously known and described thermal optical image reproducing systems has been that a comparatively large temperature change must occur between the normal operating temperature of the screen and the temperature at which a brilliant light is formed. Suitable means may be provided for increasing the thermal sensitivity of such a screen by the use of supplemental heating currents which raise the temperature of the screen to a point where the screen is only feebly visible or just below the temperature at which visible radiation occurs (that is, at low color temperature). Accordingly, it is another of the objects of my invention to provide a thermal optical image reproducing system utilizing a cathode ray beam forming a spot whose size or shape may vary in accordance with modulation potentials in conjunction with a thermal screen which is biased to a predetermined temperature.

One of the greatest drawbacks to the thermal type of optical image reproducer has been the fact that in order to get a sufficiently bright light for projection purposes the thermal screen must be raised at each bright point of the picture to an exceedingly high temperature. The result is that sections of the picture which are not as bright as the brightest portions will appear on the thermal screen as a yellowish color rather than a pure white, and accordingly different optical intensities may be reproduced in shades of color ranging from a reddish color on up through an orange and to a white, dependent upon the optical intensity of the point under reproduction. This, of course, causes an unpleasant gradation of differing color shades in what should be a black and white picture. Accordingly, it is another of the objects of my invention to provide means and apparatus for thermally reproducing an optical image in which the unpleasant gradations of color will be substantially minimized or eliminated.

In providing a constant color temperature reproduced image by thermal means, the area of the reproducing spot or the shape of the spot or a change in the focusing of the electron beam may be utilized in order to produce the constant color temperature. Of course, a combination of some or all of these means may be desirable in order to obtain correct delineation of the reproduced picture. As a result, one or more of the electrode elements of the cathode ray reproducing tube may, of necessity, be energized variably in accordance with the received signals which represent the optical image. Simultaneous energizing of all of the electrodes may not be desirable and it may be found preferable to delay the effect of a signal on some of the electrodes for a short interval of time. Accordingly, it is another of the objects of my invention to provide means and apparatus for associating the energizing of all of the electrodes necessary to produce substantially constant color temperature on the reproducing screen of a thermal image reproducing tube in such a fashion that the best delineation and optimum temperature conditions will be produced and maintained.

Accordingly, among the objects of my invention are:

1. To provide suitable structures for the thermal formation of optical images due to the energy of impact of a scanning electron beam.

2. To provide means for varying the shape of the scanning spot with reference to the direction of motion of the scanning spot in a thermal optical image reconstruction system.

3. To provide means to vary the size of the scanning spot in accordance with the variation in the modulation of the beam in a thermal optical image reconstruction system.

4. To provide a thermal optical image reproducing system utilizing a cathode ray beam forming a spot whose size or shape may vary in accordance with modulation potentials in conjunction with a thermal screen which is biased to a predetermined temperature.

5. To provide means and apparatus for thermally reproducing an optical image in which the unpleasant gradations of color will be substantially minimized or eliminated.

6. To provide means and apparatus for associating the energizing of all of the electrodes necessary to produce a substantially constant color temperature on the reproducing screen of a thermal image reproducing tube in such a fashion that the best delineation and optimum temperature conditions will be produced and maintained.

My invention in general utilizes a cathode ray tube having a thermal type of screen for reproducing an optical image. The video signal which is received and whose intensity, or amplitude, represents the optical intensity or brightness of the image reproduced not only modulates the cathode ray beam of the tube, but the same signal is utilized and the characteristics of the spot formed on the thermal screen are varied in accordance with the modulation intensity of the signal. By characteristics I mean that either the spot size or its shape or its focus on the thermal screen is varied, or a combination of these spot parameters may be availed of in order to produce a comparatively constant color temperature reproduced image on the thermal screen.

My invention will be understood best by reference to the figures in which:

Fig. 1 shows an embodiment of my invention.

Fig. 2 shows relative variation of spot size with change in signal intensity.

Fig. 3 shows a variation in the aspect ratio of the reproducing spot with change in video signal intensity.

Fig. 4 is a comparative view between the change in aspect ratio only and the change in both size and aspect ratio of the reproducing spot.

Fig. 5 shows schematically the varying of the sharpness of focus of the scanning spot with changing video signal intensity.

Fig. 6 shows an embodiment of my invention similar to Fig. 1, and in which there is included suitable time delay means.

Figs. 7, 8, and 9 are modifications of my invention.

Fig. 10 is an "aperture lens" electron-optical arrangement.

Figs. 11, 11a and 11b are modifications of Fig. 6.

Fig. 12 is a modification of the showing of Fig. 6.

Fig. 13 is an alternative form of my invention.

Fig. 14 illustrates a magnetic control system for varying the scanning spot characteristics.

Referring to Fig. 1, there is shown a system embodying my invention. This is an enlarged drawing in the plane of the electron gun of a kinescope. A heater element 10 is connected to an A. C. or a D. C. source of power, which in this case is illustrated as being the direct current source of power 11. Positioned adjacent the heater element is an emissive surface 12, and the electrons emitted therefrom pass through the aperture in a control grid 13, the latter being connected to the output of the video frequency amplifier 14, the video frequency amplifier being connected in the television receiver. The beam then passes through the aperture in the first anode 15, the latter being energized by a source of power which, in this case, is illustrated as direct current source 16. The element 16 in turn is connected to a video frequency amplifier 17, whose input is joined to the output of video frequency amplifier 14 so that the potential of the first anode swings around a median value determined by the potential value of the direct current source 16, the swing being either in phase with the potential changes of the grid 13 or in opposite phase thereto or in other phase relation thereto as may be desired. The potential source 16 may have a condenser (not shown) shunted across its terminals to permit the ready passage of video frequency charging currents. The scanning beam in the direction as indicated by the arrow identified as 18 passes through the aperture in the focusing second anode 19 which is also a positive potential, the potential being supplied by the source of direct current power 20. A condenser 21 is shunted across the terminals of the source of direct current 20, and the negative side of the source is connected to the output of a video frequency amplifier 22 having its input connected to the output of video frequency 14.

In this way the second anode 19 may also be swung in potential at video frequency either in the same or opposite or other phase relationship to the swings of the grid 13. The beam then passes through appropriate deflecting fields which are not illustrated here, but which are well known in the prior art, and impinges onto the thermal screen 23.

The object of the arrangement shown in this figure is as follows: In the bright parts of the picture, the control grid of the electron gun permits maximum beam current to flow through the gun. At the same time, the first anode permits

a maximum size of beam, and the second anode focuses it only to such an extent as to produce a scanning spot of correct size on the grid-like plate or sheet-like plate on which the thermal images are formed. If, however, a half tone or reduced brightness part of the picture is being scanned, the grid 13 cuts down the beam current, the first anode may reduce the size of the spot somewhat, and the second anode will focus the spot to a smaller size. The result is that a smaller area on the thermal image producing elements will be rendered incandescent and accordingly, while the light emitted therefrom will be reduced as compared to that corresponding to a high light, its color temperature will be almost the same. The method of delineation then comprises variable dot areas of more nearly constant color temperature rather than approximately constant dot areas of variable color temperature. By "dot" is meant the hypothetical dot element forming the television picture. The most desirable adjustment of the video frequency potential variations of the elements shown in Fig. 1 may be determined theoretically, but is probably accomplished more conveniently by experimental trial.

It will be seen therefore that this arrangement produces a picture or thermal image which has more nearly the same color in the high lights and half tones. This requires that the range of temperature with which the image is formed shall be reduced since there is a change in the color of a self-luminous body as its temperature is raised. The desired result of a more nearly constant color temperature in all delineating parts of the thermal image is accomplished by changing the size of the scanning spot in accordance with the video frequency potentials which indicate the brightness of each point of the picture. It will be understood that the electron gun structure and the circuits of Fig. 1 are purely illustrative, and that their equivalents may be similarly used without falling outside the scope of this invention.

Referring to Fig. 2, the intensity of the scanning spot is held constant, that is to say, proportionally related to the intensity of the video signal. The small scanning spot 30 corresponds to one of the darker portions of the thermal image. As the image gets brighter the scanning spot will increase in size provided a positive image is being formed, and the periphery of the larger scanning spot is shown at 31. The relative size of the smaller scanning spot 30 is shown by the distance 32 between the two arrows, and the difference in diameter is indicated by the distance 33 between the two nearer arrows. It will be understood that the size of the larger scanning spot is sufficiently small so as to enable the realization of full image detail.

Referring to Fig. 3, there is shown a variation in the aspect ratio of the reproducing spot with change in video signal intensity. The scanning spot 40 represents a spot for reproducing high lights of the picture. The spot is circular in shape, and for purposes of convenience there has been indicated that a current of 100 microamperes intensity will produce such a spot. The arrow 41 shows the normal scanning direction, that is from left to right. It will be seen that this may produce a yellow color as illustrated at 42, and the normal line width is so labeled. On the other hand, for half tone intensity the aspect ratio of the scanning spot 43 is indicated, and it will be seen that the spot is compressed from the

5 circular to form an ellipse whose major axis is along the line of scanning. In this case the spot may be produced by current value of only 50 microamperes and, as illustrated at 44, the width of the spot will be lessened but the color will remain yellow. For intensities of the video signal representative of shadow the electron beam may be of only 10 microamperes intensity and the aspect ratio is changed to a still greater degree than 10 in the case of the half tone, as illustrated at 45, and again the line width is lessened as shown at 46. In this example the aspect ratio only of the scanning spot has been changed, and the length of the scanning spot remains substantially the same.

15 Referring to Fig. 4, there is shown a comparative view between the change in aspect ratio only and the change in both size and aspect ratio of the reproducing spot. The section of this figure which is labeled "aspect ratio only varied" comprises a recapitulation of the subject matter illustrated in Fig. 3, and similar numbers have been applied to the scanning spots. In addition to varying the aspect ratio only, both the size of the scanning spot and the aspect ratio as well 20 may be varied. The spot 47 represents the same spot as that indicated at 40 and, as in the case of the spot 40, represents relatively what might be the size of a scanning spot for reproducing 25 high lights of a picture. The scanning spot 48, similarly to the scanning spot 43, would represent relatively a scanning spot for reproducing the half tone in a picture where both the aspect 30 ratio and the spot size has been varied. The scanning spot 49, similarly to the scanning spot 46, represents what relatively might be the shape of the scanning spot for reproducing the intensities representative of shadow in the picture.

35 Referring to Fig. 5, there is shown schematically the varying of the sharpness of focus of the scanning spot with changing video signal intensity. The scanning spot 50 represents a spot for low video signal intensities in reproducing a positive image, and the scanning spot 51 represents a scanning spot for higher signal intensities. The relative diameters of the two spots have been indicated by advancing through a dotted line the 40 spot 50 to be included in the spot 51, and the diameter shown is the distance 52 between the nearer arrows. It will be noticed that the modified scanning spot 51 has a vague or relatively soft contour, and apparently is larger than the sharply focused unmodified spot 50.

45 Referring to Fig. 6, there is shown an embodiment of my invention similar to Fig. 1, and in which there is included suitable time delay means. In this figure a heating element 60 has positioned in operative relationship thereto an electron emitting element 61 and the electrons emitted therefrom pass through the aperture of a control electrode 62. The beam so formed then passes through the aperture of the first anode 63 and thence between the plates forming the second anode 64. The second anode 64 is energized through the D. C. source of potential, which in this case is at battery 65, the latter being shunted by a by-pass condenser 66, the purpose of the by-pass condenser being to enable video frequency voltages to reach the element 64 without passing through the D. C. source of potential. Also connected to the second anode 64 through the battery 65 is a circuit arrangement 67 into which is fed the video signal by means of the leads 68. The element 67 may contain 50 amplifying apparatus and may also contain time

delay arrangements, since it will be appreciated that not only do the video signals have to be impressed on the control electrode 62 as hereinbefore brought out, but also may be impressed, as in this figure, onto the anode 64. Since it is preferable for optimum conditions that instantaneous modulation potentials should affect the same section of the beam regardless of the position of any particular section of the beam when affected by a particular modulation potential, it will be appreciated that an instantaneous modulation potential impressed onto the control electrode will affect a particular section of the beam, and this particular section will not reach the second anode until a short time later and the same modulation potential which has affected this section of the beam at the control electrode should then affect the same section of the beam at the second anode. Further, there may be other relative time differences between controls applied to the beam by various electrodes, and such time differences may require compensation. Hence a time control means must be inserted either with reference to the control electrode 62 or the second anode 64.

Referring to Fig. 7, there is shown an alternative form of the arrangement disclosed in Fig. 6. In this figure the first anode is indicated as 70 and the second anode as 71. The second anode is energized with a source of steady direct current potential 72 and the video signals are introduced through the amplifying and delaying arrangement 73 by way of leads 74 in parallel to the anode voltage obtained from the source 72. A video frequency choke 75 is inserted in the lead connecting the anode voltage to the cathode tube. A condenser might also be inserted in the lead 76 to isolate the circuit arrangement 73 from the high voltage anode source.

Referring to Fig. 8, there is shown a somewhat similar arrangement to the showing in Fig. 6. In this case, however, the video potentials are impressed by means of leads 80 onto the first anode 81 of the cathode ray tube through the source of direct current potential 82, the latter being shunted by a by-pass condenser 83. The delay and amplifying circuits are contained in the square identified as 84 similarly to the manner described with respect to the elements 67 and 73 of Figs. 6 and 7, respectively. The second anode is indicated as 85.

Referring to Fig. 9, there is shown an arrangement which is alternative to the showing of Fig. 7. In Fig. 9 the video signals are impressed by means of leads 90 through delay and amplifying circuits 91 onto the first anode 92 of the tube rather than the second anode as illustrated in Fig. 7. Similarly the lead 90 might have a condenser inserted serially therewith to prevent impressing of the anode voltage from the source 94 onto the circuits contained in 91. A video frequency choke 95 is inserted in series with the source of anode potential to suppress the impression of video frequency signals onto the circuit containing the source of anode potential. The second anode is indicated at 96.

There has been brought out above that to control the size and/or sharpness of focus as well as the electron optical aberrations in the spot, there is required video signal control variation of the scanning spot focusing means. Such focusing means may be either an electrostatic lens of any type or a magnetic focusing means of any type, or by any combination of the above.

It is also possible to throw the scanning spot out of focus to any desired extent by the video signal, or to change its size, or to alter its optical aberrations through the use, for example, of the so-called "electron aperture lens" which may be of the so-called divergent type, the degree of divergence being video signal controlled. Errors in the electron optics of the scanning spot production, as well as changes in the aspect ratio thereof, can be introduced by decentering or asymmetry of the electron optical electrodes or apertures therein or the shape thereof.

Referring to Fig. 10, there is shown schematically an example of the so-called "aperture lens." This consists of a large fiat surface 100 on which there is placed an electron emitting material 101 and in front of and close to which is a parallel plate 102 in which is the focusing aperture 103. In this instance, the video signal control voltages are applied to the element 102.

Referring to Fig. 11, there is shown a typical arrangement wherein the second anode 110 of the tube is elliptical in cross-section rather than circular, as indicated in the view thereof shown in Fig. 11b, and in which the anode is identified as 111.

In this figure the neck of the tube is shown in cross-section with the elliptically shaped second anode. This element is made elliptical deliberately to introduce eccentricity or astigmatism into the scanning spot, and to enable, if desired, the video signal control of the degree or extent of such eccentricity by impressing the video signals onto the second anode 110. The first anode 112 remains of circular cross-section as indicated in Fig. 11a, in which the neck of the tube is shown in cross-section and the circular shaped anode is identified as 112. Alternatively, the first anode 112 could be given an elliptical cross-section and the apertures 114 and 115 within the plates might be made elliptical for the same purpose. Accordingly, it will be seen that either or both of these anodes may have an elliptical cross-section.

Referring to Fig. 12, there is shown an arrangement for deliberately introducing eccentricity or astigmatism into the scanning spot by decentering either or both the first anode 120 or the second anode 121 relative to the axis of symmetry 122 of the beam. In this figure the heating element 123 is energized by either alternating or direct current and causes electron emission from the electron emissive material 124. These electrons are concentrated into a beam and may be modulated by the control electrode 125.

Referring to Fig. 13, there is shown a different and alternative method of controlling the scanning spot characteristics by the video signal. In this figure there is shown the heating element 130 with the electron emissive material 131 and the apertured control electrode 132. The first anode is shown at 133 and the second anode at 134, the latter being energized by a source of steady direct potential 135. In addition to the first and second anodes 133 and 134 respectively, there is a third or supplementary electrode 136 to which there may be applied the video signal voltages from the leads 137 and the amplifying and delaying arrangement 138. Of course, biasing potential may also be applied to the supplementary anode 136 in such manner as indicated, for instance, in Figs. 6 and 7.

The arrangement as indicated in Fig. 13 has the advantage that it enables the independent control by the video signal of the scanning beam characteristics other than the intensity. It will

be understood that the intensity of the beam may be varied slightly and to a minor extent by the means shown in the figures of this specification for the control of the other characteristics of the scanning spot. However, these methods shown will predominantly and primarily and substantially entirely control other characteristics of the scanning spot than its intensity.

Referring to Fig. 14, there is shown an apparatus for the magnetic method for video signal control of the scanning spot characteristics other than its intensity. In this arrangement the coil 140 is the usual magnetic focusing coil and this is supplied with a substantially constant focusing current from direct current source 141. In view of the high inductance of the average magnetic focusing coil an additional coil 142 is provided having a lower inductance than that of the coil 140 and this coil is provided to control the characteristics of the scanning spot. The video signal current is impressed on this coil from leads 143 through suitable amplifying and, if desired, delaying apparatus 144.

It will be appreciated that there may be departures of the particular arrangements hereinbefore illustrated which will fall fairly within the spirit and scope of my invention and I am not limited to the exact showings, but claim all such modifications as fall fairly within the spirit and scope of the hereinafter appended claims.

What I claim is:

1. In an electro-optical image reproducing system, means for developing a cathode ray beam, a thermally responsive target positioned to receive the said electron beam to develop light at the area of beam impact, and means operating under the control of applied signal modulation potentials to alter at least one of the cross-sectional dimensional parameters of aspect ratio and shapness of focus of the impact point formed by the electron beam on the target to maintain substantially monochromatic image reproduction from the target.

2. In an electro-optical image reproducing system, means for developing a cathode ray beam, a thermally responsive target positioned to receive the said electron beam to develop light at the area of beam impact, and means for modulating the said developed electron beam under the control of applied signals, said modulation being adapted to vary the total electron beam current in substantial proportion to the modulation signal and simultaneously to maintain the beam current density across the cross-sectional areas of the said beam substantially constant so that the light image developed upon the said target is substantially monochromatic.

3. In an electro-optical image reproducing system, means for developing a cathode ray beam, means for modulating the intensity of the beam under the control of signals indicative of the optical values of the optical image to be reproduced, a target means for producing light in accordance with the impingement of the electron beam thereon, means for accelerating the cathode ray beam in the direction of the target and means for impressing signals representative of the optical image onto said electron beam accelerating means whereby at least one of the cross-sectional dimensional parameters of said

beam at the scanning spot are altered in accordance with the value of the signals impressed on said accelerating means to enhance the accuracy of reproduction of the reproduced image.

4. Apparatus in accordance with claim 3, wherein said electron beam accelerating means comprises a plurality of anode electrodes upon each of which the signals representative of the optical image are impressed.

5. Apparatus in accordance with claim 3, and wherein there is provided in addition time delay means for controlling the time of impression of the signals indicative of the optical values of the image to be reproduced onto at least one of the beam modulating electrodes relatively to the other beam modulating electrodes.

6. Apparatus in accordance with claim 3, comprising, in addition, a time delay circuit between said beam modulating and accelerating means so that signals representative of the optical intensities of the optical image to be reproduced may be applied with predetermined time delay to the modulating and the accelerating means for controlling said cathode ray beam.

7. Apparatus in accordance with claim 3, wherein said anode means for accelerating said electron beam has at least a portion thereof having an elliptically shaped cross-section.

8. In an optical image reproducing system in which signals are received indicative of the intensities of the optical values of the image to be reproduced, and in which the image is reproduced by the thermal effect of a cathode ray beam impacting an incandescing electrode, the method of maintaining a constant color temperature in the screen over a range of signal variations which comprises the steps of generating a cathode ray beam and directing the generated beam toward the incandescing electrode, modulating the current value of said beam in accordance with the value of the instantaneous signal potentials so as to alter at least one of the cross-sectional dimensional parameters of aspect ratio and focus of said beam in accordance with the same instantaneous signal values so as to maintain substantial monochromatic image reproduction from the incandescing electrode.

9. In an optical image reproducing system in which signals are received indicative of the intensities of the optical values of the image to be reproduced, and in which the image is reproduced by the action of the electron beam on a thermally responsive target electrode, the method of reproducing the optical image which includes the steps of generating a cathode ray beam and directing the beam toward the target electrode and modulating the current value of said electron beam in accordance with the instantaneous values of the signals representative of the optical image to be produced upon the target by varying the total electron beam current in substantial proportion to the said signals and simultaneously maintaining the beam current density across the cross-sectional areas of the said beam substantially constant, so that the resultant image developed upon the target electrode is substantially monochromatic in character.

ALFRED N. GOLDSMITH.
